UNITED STATES PATENT OFFICE.

ERNST KAUFMANN, OF SOLINGEN, GERMANY.

CUTTER AND IMPLEMENT FOR THE NAILS.

SPECIFICATION forming part of Letters Patent No. 730,024, dated June 2, 1903.

Application filed November 14, 1902. Serial No. 131,329. (No model.)

To all whom it may concern:

Be it known that I, ERNST KAUFMANN, a subject of the German Emperor, residing at Solingen, in the German Empire, have invented 5 certain new and useful Improvements in Cutters and Implements for the Nails, of which the following is a specification.

The present invention relates to an improved cutter and implement for the nails and is constructed after the manner of small tweezers or nippers, but which by reason of the shape of one leg allows of a gentle cut being made without requiring any considerable exertion of power. The said leg is also made 15 on its inner side as a nail-file or nail-cleaning implement, so that the improved implement is suitable for the complete care of the nails.

One method of carrying this invention into effect is illustrated, by way of example, in the 20 accompanying drawings, in which—

Figure 1 is a view in front elevation of the implement in the closed condition. Fig. 2 is a view in side elevation thereof. Fig. 3 is a similar view showing the cutter in an open 25 position; and Figs. 4 and 6 are views in front elevation outside and inside, respectively, showing the file or cleaning-tool turned up. Fig. 5 is a view in side elevation of Figs. 4 and 6, and Figs. 7 and 8 are views from above of the 30 cutting-jaws in the closed and opened positions, respectively.

Throughout the views like parts are marked with like letters of reference.

In the construction shown the nail-cutter is 35 provided with inclined and conically-bent cutting-faces *x* and *y*; but this particular construction is not a distinguishing feature of the invention, because they may also be formed as straight cutting-faces. The small jaws 40 which carry the cutting-faces *x* and *y* are extended in the form of levers or arms and are pivoted together by means of a hinge *s*. The leg of the jaw *y* is shorter than the opposite leg and has pivoted to it in a slot *a*, Fig. 1, 45 the lever *h*. This lever has its upper part pivoted on the pin *t*, formed with a wedge-shaped nose, while its lower part is formed internally as a file and its free end as a nail scraper or cleaner. The free end of the leg 50 belonging to the jaw *y* is acted on by a forked spring *f*, which is fixed to the leg of the jaw *x* by means of small screws *m* and *n*, the said

spring being so arranged as to have a tendency to continually move the jaws away from each other.

The pivoted lever *h* in moving from the open position, Fig. 3, into the closed position, Fig. 2, will cause the lower ends of the legs belonging to *x* and *y* to be moved away from each other by reason of the higher back of the 60 nose of the lever *h* coming in between them, so that the jaws are thereby moved toward each other and the spring *f* is placed under further tension. When the nail-cutter is in the closed state, it is secured by means of a 65 loop or catch *v*, which is movably connected at *p* to the leg of the jaw *x* and which is slipped over a groove in the lower end of the lever *h*.

Thus to use the nail-cutter the catch *v* is 70 opened out of the position shown in Fig. 2 in a downward direction, whereupon the jaws of the cutter open, Fig. 3, and the lever *h* assumes the cocked-up position. If now the nail be placed between the cutting-faces and the leg *h* be moved toward the opposite leg, the eccentrically-disposed nose of the lever *h* will produce a considerable leverage and increase of power, so that the nail will be cut off gently; but if the lever *h* be moved still 75 farther up out of the position shown in Fig. 3, so that its extreme edge nearest to the jaw be now situated undermost, then the cutter will be again in its open position, but so as to cause the spring *f* to lock, as it were, the 80 lever *h* in that position, Fig. 5. The lever *h* is thus locked in position to serve as a file, and it may then be used as such, as also with its free end, that is now situated uppermost, 85 as a nail cleaning or scraping device.

The forked shape of the spring *f* is necessary in order to allow of suitably mounting the lever *h*. This improved implement for the nails, notwithstanding its extremely effective action, is of such small dimensions 90 that it can be easily carried in the waistcoat pocket or the like.

What I claim, and desire to secure by Letters Patent of the United States, is—

1. A device of the class described comprising pivotally-connected legs having cutting-jaws at one end, one of said legs being shorter than the other, said shorter leg being bifurcated, a lever pivoted between the resultant 100

spaced portions of the shorter leg, said lever having a cam disposed for engagement with the opposite leg and movable to engage portions at opposite sides of its point of greatest eccentricity and a spring constructed and arranged to hold the legs yieldably against the action of the cam, said lever being provided with nail-treating devices.

2. A device of the class described comprising pivotally-connected legs having cutting-jaws at one end, one of said legs being shorter than the other and bifurcated to form spaced portions, the ends of said spaced portions being beveled, a lever pivoted between the spaced portions and having a cam disposed

for engagement with the opposite leg and movable to engage portions at opposite sides of its point of greatest eccentricity, said lever being provided with nail-treating devices, and a spring attached to the end of the longer leg and disposed for its free end to bear upon the beveled ends of the spaced portions of the shorter leg to hold the leg yieldably against the action of the cam.

In testimony whereof I have hereunto set my hand in the presence of two witnesses.

ERNST KAUFMANN.
